Henry Hebbard & John Polhamus of New York, N.Y.
Letters Patent No 715 Dated July 3rd 1855

—————
The Schedule referred to in these Letters Patent and making
part of the same.

—————

To all whom it may concern

Be it known that we Henry
Hebbard, and John Polhamus of the City, County and State
of New York, have invented or produced a new and ornamen-
tal design for ornamenting the handles of Spoons and other
articles of table cutlery, and we do hereby declare the following
to be a full description of the same reference being had to the
accompanying drawings forming a part of this specification

the same letters of reference wherever they occur referring to like parts.

Figure 1. is a front view of the spoon.

" 2 is a back " " same.

Letter a, is a representation of the shield of the spoon. Around the edge of the front side of it, are two threads b, b, and at the upper end or head of the shield, are four scroll figures c, c, & c, c, opposite each other, and somewhat shaped like a section of the convolvulus with their stems entwining each other, and terminating in a narrow headed figure d, having two drops pendant from its lower point and terminating near the centre of the shield piece, complete the ornament on the upper end or head of the front of the shield piece.

At the lower end of the front shield piece, where it joins on to the stem e, of the spoon, are also two scroll figures f, f, somewhat like those at the head of the shield, having their branching ends or mouths opening outwards and downwards, and their stems branching upwards in a scroll and terminating in the upper point of the open figures f, f.

Under laying these figures is also a representation of a loop g, having its lower ends crossing each other between the points of the two figures f, f. the whole resting upon capitals h, h, forming the head of the column or stem of the spoon, and shaped somewhat like a tulip cup.

Down the stem, are raised two threads i, i, on each side of a column of beads j, which gradually diminish in size from the head of the stem to the terminating figures m, m, at the shank k, or point of junction with the bowl l, of the spoon.

These shank figures m, m, are composed of similarly branching figures to those described as ornamenting

The head of the shield piece, having their branching ends opening outwards and upwards, and their stems crossing each other and turning upwards, thereby completing the design for ornamenting the front of the spoon.

The reverse side of the spoon is ornamented at the head of the shield piece a, by two scroll or branching figures n,n, similar to those referred to on the front side of the spoon. The branching ends of these two figures open outwards and downwards, having their stems crossing each other in a scroll form and terminating at the back of, and between the branching ends of the figures n,n.

Around the back shield piece are two threads p,p,q, the latter having its upper end branching and supporting the figures n,n, and its lower end terminating or resting upon the branching head r,r, of the thread surrounding the lower ornament of the shield piece.

This ornament is composed of two branching figures s,s, like those before referred to, and have . . their branching ends opening outwards and upwards somewhat like the mouth of the cornucopia and their stems turned up, and supported upon capitals t,t, forming the termination of the upper end of the stem of the spoon and of the double raised threads u,u, on the margin of the stem.

Between these raised threads, the stem of the spoon is slightly concave, as shown at v.

At the heel of the bowl, it is ornamented with four figures w,w, having branching ends with their stems crossing each other in such a way as to form a triangular leaf-like figure or ornament to cover the heel of the spoon, and then terminating in the threads forming the marginal lines of the stem, to complete the ornamental design for the back side of the spoon.

Having now described our invention and its application to spoons and other articles, we will state what we

claim and desire to secure by Letters Patent of the United States.

What we claim is the use and arrangement of the ornamental devices hereinbefore described for ornamenting the front of the spoon, and back of the spoon, or either of them in combination with the spoon or other similar articles of table cutlery.
